UNITED STATES PATENT OFFICE.

ALBERT T. WEISS, OF ROCHESTER, NEW YORK, ASSIGNOR TO YAWMAN & ERBE MFG. CO., OF ROCHESTER, NEW YORK, A CORPORATION OF NEW YORK.

EXTENSION-DRAWER.

1,178,609.

Specification of Letters Patent. Patented Apr. 11, 1916.

Application filed August 23, 1911. Serial No. 645,633.

To all whom it may concern:

Be it known that I, ALBERT T. WEISS, of Rochester, in the county of Monroe and State of New York, have invented certain new and useful Improvements in Extension-Drawers; and I do hereby declare the following to be a full, clear, and exact description of the same, reference being had to the accompanying drawings, forming a part 10 of this specification, and to the reference-numerals marked thereon.

My present invention relates to furniture and more particularly to furniture drawers and has for its object to provide an improved means of the extension type for supporting a drawer in its open position.

A further object of the invention is to provide for the convenient and ready removal of the drawer and its complete detachment from its support, when desired, and the improvements are further directed to simplicity of parts and economy in manufacture.

To these and other ends the invention consists in certain improvements and combinations of parts all as will be hereinafter more fully described, the novel features being pointed out in the claims at the end of the specification.

30 In the drawings: Figure 1 is a side elevation of a drawer and its casing constructed in accordance with and illustrating one embodiment of my invention; Fig. 2 is a similar view with the drawer ready to be 35 completely detached from its casing; Fig. 3 is a horizontal section taken substantially on the line 3—3 of Fig. 2, showing in plan view the front portion of the drawer and its supporting parts, and Fig. 4 is a detailed 40 perspective view of the forward end of one of the extension supports.

Similar reference numerals throughout the several figures indicate similar parts.

The casing or cabinet 1 as shown in the 45 present embodiment, is of a skeleton structure embodying front, intermediate and rear vertical rails 2, 3 and 4 and the whole forms a chamber in which operates the drawer 5. As the drawer is hung in the same manner 50 on each side a description of one of these sets of hanging devices will suffice for both.

The extension support 6 is arranged between the side of the drawer and the side wall of the casing and slides in and out in

a guideway formed between upper and lower 55 cleats 7 and 8 secured to the rails 2, 3 and 4. The lower side of the upper cleat 7, the upper side of the lower cleat 8 and both the upper and lower sides of the extension support 6 are provided with grooves 9 forming 60 tracks that receive and retain anti-friction rollers 10 which I prefer not to mount on fixed axes but allow to roll freely. It will be understood that the extension support may thus be moved a limited distance to 65 project forwardly from the drawer chamber and to react against the cleats 7 and 8, as is usual in such devices.

The forward end of the extension support is bifurcated to form a horizontal 70 guideway 11, the forward end of which is open at the front end of the support, while the rear end is closed and provided with a suitable buffer 12. Traveling in this guideway is a laterally projecting supporting 75 member 13 secured to the side wall of the drawer 5 and, in the present instance, provided with spaced anti-friction rollers 14 and 15 for coöperation with which tracks or grooves 16 are formed on the upper and 80 lower sides of the guideway 11. These tracks 9 and 16 together with their respective rollers prevent the lateral disengagement of the support 6 from the casing and 85 of the drawer from the support.

The forward end of the guideway 11 is normally closed by an abutment 17 preferably carrying a buffer 18 that enters between the tracks of the guideway, which abutment is in the form of a yoke, the horizontal arms 19 of which are pivoted at 20 to the extension 6 on opposite sides of the guideway 11 or to the respective separated parts thereof left by the bifurcation, while the intermediate portion carrying the beforementioned buffer 18 extends vertically 90 across the end of the extension and spans the guideway in the path of the supporting member 13 on the drawer, or more particularly its forward roller 15.

In the ordinary operation of the device, when the drawer is pulled forwardly the extension 6 moves forwardly on its own guideway for a limited distance defined by the arrival of the anti-friction rollers 10 at the 105 ends of their tracks 9 so that its forward end projects a considerable distance from the drawer chamber. The drawer also

moves forwardly in the guideway 11 on the extension support 6 until the roller 14 strikes the abutment 17, or rather its buffer 18, with the net result that the drawer is allowed an extreme open position in which its rear end is substantially coincident with the front face of the cabinet or casing and its entire interior is rendered accessible. A similar but reverse action takes place when the drawer is thrust into its chamber, the anti-friction rollers 10 moving to the opposite ends of their tracks and the rearward roller 15 on the drawer cooperating with the buffer 12 at the rear end of the extension support to halt its own movement and also to insure the complete inward movement of the extension.

When it is desired to remove the drawer entirely from the cabinet or casing and detach it from the supports the abutment 17 is simply swung laterally to the position shown in Figs. 2 and 3 at which it lies at the side of the guideway and is no longer in alinement with or in position to close the open forward end of the latter. It is therefore only necessary to continue the forward movement of the drawer to cause the supporting projection 13 thereon, and its rollers, to issue from the guideway 11 and the drawer is then free. In reinserting the drawer, the rear roller 15 may be easily inserted in the open end of the guideway 11 with the parts in the same position of Figs. 2 and 3 and, after bringing the other roller 14 in horizontal alinement therewith shove the drawer into its position on the extension support 6. As it is subsequently pushed into the chamber, the roller 15 will engage the buffer 12 at the inner end of the guideway 11 and cause the extension 6 to move to its extreme closed position also. In so doing, the yoke-shaped abutment 17, which is then in its lateral position, is engaged by a stop, furnished in the present instance by the front rail 2 of the cabinet, as clearly shown in Fig. 3, and caused thereby to swing forwardly to its operative position at the front end of the extension and to again close the open end of the guideway 11, as before. The readjustment of the parts whereby the drawer is locked against disengagement from the supports is thus automatically effected merely by continuing the closing movement of the drawer after its supporting projection is once inserted in its guideway.

A device constructed in accordance with my invention will be found to offer great advantages particularly when it is desired to detach or replace drawers that have considerable weight or are heavily laden, the necessary manipulation of the drawer consisting merely in raising it vertically to the proper level and then thrusting it in a horizontal direction, while the end of the guide-

way 11 in which the roller 15 must be initially inserted is at the same time in full view as well as is its coöperating part.

I claim as my invention.

1. The combination with a drawer and a support therefor, one of said parts being provided with a guideway arranged laterally of the drawer comprising upper and lower tracks and the other with a drawer supporting member traveling in the guideway as the drawer is operated, of a permanently attached but movable abutment at one end of the guideway normally extending across the latter from one track to the other and secured on opposite sides of both tracks to prevent the drawer supporting member from being withdrawn from the guideway, said abutment being movable while still connected to the guideway to a position at one side of the latter to permit the removal of said drawer supporting member.

2. The combination with a drawer and a support therefor, one of said parts being provided with a guideway comprising upper and lower tracks and the other with a supporting member traveling in the guideway as the drawer is operated, of a movable abutment at one end of the guideway embodying a yoke shaped member having its arms pivoted to the part on which the guideway is formed and its intermediate portion normally spanning the guideway to prevent the supporting member from being withdrawn from the latter, the abutment being adapted to be swung on its pivot to carry the said intermediate portion to one side of the guideway and permit the removal of the supporting member from the latter.

3. The combination with a drawer and an extension support therefor, the latter being bifurcated at one end to form a guideway and the former being provided with a supporting member movable in the guideway as the drawer is operated, of an abutment on the extension support embodying a yoke shaped member having its arms respectively pivoted on each side of the guideway and its intermediate portion adapted to swing laterally into and out of a position in which it closes the open end of the guideway against the withdrawal of the supporting member.

4. The combination with a casing forming a drawer chamber and a drawer and an extension support therefor arranged laterally of the drawer operating therein, one of said last mentioned parts being provided with a guideway open at one end and the other with a drawer supporting member traveling in said way as the drawer is operated, of an abutment mounted on the part in which the guideway is formed and movable into and out of a position in which it closes the open end of the latter against the withdrawal of the drawer supporting member therefrom, and a stop on the casing arranged to engage

the abutment and actuate it to such closed position automatically with the closing movement of the drawer.

5. The combination with a casing forming a drawer chamber and a drawer and an extension support therefor operating in the chamber, the extension support being arranged between the drawer and casing and provided with a guideway open at the forward end thereof and the drawer being provided with a supporting projection traveling in the guideway as the drawer is operated, of an abutment pivoted to the extension support to normally close the end of the guideway against the withdrawal of the supporting projection on the drawer and movable laterally to permit such withdrawal and a stop on the casing arranged to coöperate with the abutment when in such lateral position and move it to closed position automatically as the extension support is thrust inwardly within the drawer chamber.
- 10 15 20

6. The combination with a casing forming a drawer chamber, a drawer operating there-

on, an extension support for the latter arranged between the drawer and casing and provided with a guideway open at its front end and at the front end of the extension support and a supporting projection on the drawer traveling in the guideway as the drawer is operated, of an abutment on the extension support embodying a yoke shaped member having its arms respectively pivoted on each side of the guideway and its intermediate portion adapted to swing laterally 35 into and out of a position in which it closes the open end of the guideway against the withdrawal of the supporting projection on the drawer, said abutment being arranged to be engaged by the wall of the chamber and moved to closed position automatically when the drawer and its supporting extension are moved inwardly into the drawer chamber.
